Self-acting Cylinder

The schedule referred to in the Patent, and making part of the same containing a description of the ends of the said cylinder
in respect of the improvement in the mode of causing cloth to pass and be
stretched whilst passing over a revolving cylinder prepared with points
for tearing or rasing the pile on nap upon cloth.

It will be observed that the date given above mentioned
relates to when this invention shall come to my knowledge
in the County of Worcester and State of Massachusetts, and
not to the date of my application for a patent. — It is known that I the said Inventor have made
and exhibited made and applied to use a new and useful improvement
in the mode of causing cloth to pass and be stretched whilst passing over
a revolving cylinder prepared with points, or teeth, for tearing or rasing
the pile on nap upon cloth, which invention and the improvements
of and the occasions in which I have contemplated the application thereof,
and the mode of using the same are explained and described as follows,
that is to say. The cloth to be treated is to be found on a revolving cloth
beam and from that made to pass over and under rollers and over the
revolving cylinder prepared for tearing it, and over and under rollers
on to another revolving cloth beam on which it is to be wound up as
it comes off from the first beam after having passed over and under
the rollers and cylinder prepared, and thereby a change of nap is
made at the beam around from the first beam it may be made
to pass back over and under the rollers and cylinder prepared
and again around upon the first beam as it comes off from the beam
on which it was last around up. The action of the cloth beam and
rollers being given to rotate and change in the manner herein after
described and as given a which description and explanation may
be better understood by referring to the following heads or points.
The cloth being wound on the cloth beam mentioned in point A.

is made to pass over the carrying roller numbered four hundred thirteen under the feeding roller numbered thirteen and then over the stretching roller numbered fifteen and thence under the metallic roller numbered sixteen and thence over the roller for tension it numbered seventeen and thence under another metallic roller numbered eighteen and thence over stretching roller numbered nineteen and thence under a fixed roller numbered twenty and thence over a carrying roller numbered twenty one and thence onto the cloth beam numbered twenty two upon which it is wound up when the machine is in motion and it passes as aforesaid from the cloth beam numbered twenty two and from which cloth beam numbered twenty two it may be observed that certain beam described to be made to pass back and forth and up upon the cloth beam numbered twelve. The cloth beam may run back and forth and twenty two in plan A and have pulleys of the same diameter of the beams on both ends thereof and fastened to the same shaft by which the beam is moved, which pulleys are numbered by XX. In the plan B the pulleys are connected with pulleys upon their respective feeding rollers numbered thirteen and twenty one in plan A by means of cords or belts running over the pulleys and also over pulleys at the ends of the respective feeding rollers and fixed to their shafts, which pulleys are of the same diameter as the feeding rollers respectively by which means motion is communicated from the feeding rollers to the cloth beam. Rollers numbered fourteen and twenty one in the plan A are isolated scudding rollers called carrying rollers and are moved merely by the friction of the cloth passing over them. Rollers numbered thirteen and twenty one in plan A are rollers moved by means of a belt feeding rollers which draw the cloth and stretch it out, &c. &c. &c. Roller numbered fifteen in the same plan is a scudding isolated roller moved only by the cloth capable of being elevated and depressed to pass over the cloth and gradually to stretch upon the front or back of the cylinder prepared for carrying it. Roller numbered sixteen is an isolated roller and moved only by the force of the air.

of the cloth passing over it called a knitting roller. Number twelve is sixteen and eight are two metalated rollers to be made of iron or any other metal sufficiently stiff and strong enough only by the friction of the cloth and intended to keep the cloth smooth while it reaches the points or teeths on the cylinders of frames for traying it. Their invention is the cylinder prepared with points or teeths for passing the pieces or nap on cloth. H, F, C & G in plain Arabic wheel. H & G being each one hundredth larger in circumference than F & C. The gear wheel H & G are fixed to their respective shafts immovably and move with and turn them. F & C are not always so fixed but move upon their respective shafts when revolving in one direction and become fixed when revolving in an opposite direction and brought so that the catches upon and connected with them are perfectly catched into the crenulations fixed to their respective shafts. Q & R. K & B. are circular and totally fixed to their respective shafts Q & R for the purpose of holding the gear wheels. F & C when revolving and brought so that their catches are catched into the teeth of the ratchets L & M on a spring and catch connected to the gear wheel F and the ratchet K into which the catch catches when the gear wheel is turned in such direction and brought so that the catch comes into the teeth of the ratchet so as to hold the wheel. There is a similar spring and catch on the gear wheel C which catches into the ratchet B in like manner and for like purpose. S is a lever called a shippring lever used to put in and out of gear the gear wheels F & G alternately and also to put in and out of gear the friction wheel V & V on shafts of the cloth beam on the outside of the frame marked X & X on shafts of the cloth beam numbered twelve and twenty two. T is the shaft marked friction, D & J. makes the shaft is stationary and is bent in the middle so as to bring each end in the centre of the respective pinions D & J. I & J are pinion wheels with a flange connected with catches U, U, U, U and not confined but loose on the shaft and pass respectively into the respective

gear wheels, E & G. H & C. D & F are pulleys fixed on the shaft P. and move in contrary ways by belts, one being an open and the other a cross belt for the purpose of changing the motion of the cloths T.T.T. in dogs which pass through the pulleys D & F respectively and receive with them and by means of the shifting lever may be brought so as to be held fast by the catchers U.U.U on the flanges of the pinions I & J. when it is required to change the motion of the cloth roller, a necessary motion being given to the pinions I & J respectively by being thus connected with the respective pulleys D & F which are always moving with the same velocity in a contrary direction to each other. Lever S. turns on a pivot X and is connected with fork Y & W. which are adjusted to the width of the flanges in which are the dogs T.T.T. so that the flanges may not slide while the forks remain stationary and so that the forks, being adjusted to the width of the flanges may by a motion of the lever move the dogs T.T.T. so as bring them in contact with, or remove them from the catchers U.U.U.U. as may be required. Lever S. extends to the opposite side of the frame, and the marked O in floor A is connected with rod Y.Y. in floor B which is attached to a perpendicular lever Z which turns upon the pivot A.A. and is made to act by motion of the lever S on a horizontal side membered twenty three running parallel with the opposite side of the frame and the side membered twenty three in the floor B is connected with a lever numbered twenty four which is opposite and parallel to lever B and turns on a pivot B.B. in the centre between the cloth beams numbered twelve and twenty two. so that when lever S is moved it operates on lever numbered twenty four. Twenty four and turns by pivot on floor B on fork, attached to lever numbered twenty four, said bayonet, or slide numbered twenty six, and turns in such manner as when lever D.F is moved in one direction it moves the bayonet or slide membered twenty six in contact with dogs 28 and carry the friction pulley V to rest on cloth.

gear wheels, E & G. H & C. D & E are pulleys between the shafts P. and moved contrary ways by belts, one being an open and the other a cross belt for the purpose of changing the motion of the cloth. T.T.T.T are dogs which pass through the pulleys D & E respectively and are to be in contact with them and by means of the shiftpins here may be brought so as to be held fast by the catches U.U.U.U on the flanges of the pinions I & J. when it is required to change the motion of the cloth rollers a revolution being given to the pinions I & J respectively by being thus connected with the respective pulleys D & E which are always moving with the same velocity in a contrary direction to each other. Lever S. turns on a pivot X and is connected with pulley W & X. which is adjusted to the width of the flanges in which are the dogs T.T.T.T so that the flanges may revolve while the pulley remains stationary and so that the forks, being adjusted to the width of the flanges may by a motion of the lever move the dogs T.T.T.T. so as bring them in contact with, or remove them from the catch U.U.U.U as may be required. Lever S. extends to the opposite side of the frame and the marked O in plan A is connected with rod Y.Y. in plan B which is attached to a perpendicular lever Z which turns upon the pivot A.A. and is made to act by motion of the lever S on a horizontal side member having thereon a sliding parallel with the opposite side of the frame and the slide numbered twenty three in the plan B is connected with a lever numbered twenty four which is opposite and parallel to lever B and turns on a pivot B.B. in the centre between the cloth frame numbered twelve and twenty two. so that when lever S is moved it operates on lever numbered twenty four. Twenty four and turns by gear in plan B on pivot attached to lever numbered twenty four, and having on slide numbered twenty six, a rod having a screw in such manner as when lever O is moved in one direction it throws the bayonet or slide numbered twenty six in order with dogs 28 and causing the friction pulley V to act on cloth.

time a communication of motion to have numbered twenty four, the pulley
number V is made to act on the cloth beam numbered twenty two. Now when B do
es to bring the dogs "T, T", in contact with the catches upon one wheel J on the
opposite side and the opposite motion will take place both with respect to the
gear wheels ... rollers and cloth beams. When the machine is in motion and
the cloth is passing from the cloth beam numbered twenty under the feeding roller
numbered thirteen and so on in the manner before described to the cloth beam
numbered twenty two the pulley V is acting on the cloth beam numbered
twelve for the purpose of preventing the cloth from going off too fast, and the
feeding roller numbered twenty two, moves with a velocity one twentieth part
less than the feeding roller numbered thirteen by reason of the inequality in size
of the gear wheels E + C in order to draw the cloth tight and smooth over the
cylinder prepared for tearing it and the cloth beam numbered twenty two
is moved so as to wind up the cloth by motion communicated from a pulley
on the shaft of the feeding roller numbered twenty, by means of a belt which
will slip so as to accommodate the velocity of the cloth beam to its varying
circumstances by means of the winding of the cloth upon it. When the cloth
is passing from the cloth beam numbered twenty two under the feeding roller
numbered thirteen and so in the manner described to the cloth beam num-
bered twelve the pulley V is acting on the cloth beam numbered twenty
two for the purpose of preventing the cloth from going off too fast and the
feeding roller numbered thirteen moves with a velocity one twentieth
greater than the feeding roller numbered twenty by reason of the inequality
in size of the gear wheels H + C in order to draw the cloth tight and smooth
as aforesaid and the cloth beam numbered twelve is moved so as to wind
up the cloth by motion communicated from a pulley on the shaft of the
feeding roller numbered thirteen by means of a belt which will slip
so as to accommodate the velocity of the cloth beam as aforesaid. It
is to be understood, nevertheless, that although I have in my plan, and
the application being mentioned a cylinder prepared with points or
tangles for tearing cloth, yet I do not claim as a part of my inven-
tion such cylinder either separately or in combination with the tearing
of cloth on cloth by means thereof and although I have mentioned which

X C 313

212.

allow numbered fifteen and seventeen on my plan A which ought to be
the stock-taking and the now used for stock-taking the cloth widthwise. yet I do
not claim this ^{other} especially or in combination as a part of my invention
nor the stock-taking of cloth widthwise. and as to the rest of the machine
as described some of it is claimed separately and only you, much of it in
combination as is adapted to give motion to and regulate and change
the motion of the feeding rollers numbered thirteen and twenty in my
plan A so as to regulate and change alternately, the working of the cloth
and draw it tight and smooth over the cylinder of each and for raising
the nap ^{up} - - - - - In witness whereof the said John Everett has
hereunto set my hand and seal this seventh - day of December in the
year of our Lord Eighteen Hundred and Thirty.
